J. F. LE BARON.
INSECT CATCHER.
APPLICATION FILED JAN. 18, 1915.

1,148,910.

Patented Aug. 3, 1915.

UNITED STATES PATENT OFFICE.

JOHN FRANCIS LE BARON, OF CHARDON, OHIO.

INSECT-CATCHER.

1,148,910.

Specification of Letters Patent.

Patented Aug. 3, 1915.

Application filed January 18, 1915. Serial No. 2,924.

To all whom it may concern:

Be it known that I, JOHN F. LE BARON, a citizen of the United States, residing at Chardon, in the county of Geauga and State of Ohio, have invented a new and useful Insect-Catcher, of which the following is a specification.

The device forming the subject matter of this application is adapted to be employed for killing, stupifying and collecting insects.

One object of the invention is to provide a device of the type indicated in which a blower may be operated in one direction to expel poison and then be operated in a reverse direction to suck in the poisoned insects.

It is within the scope of the invention to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawing:—Figure 1 shows the invention in vertical longitudinal section; Fig. 2 is a top plan, the cover of the casing being removed; Fig. 3 is an elevation delineating a modified form of nozzle; Fig. 4 is a bottom plan of the suction head; Fig. 5 is a vertical section of the suction head; Fig. 6 is an elevation showing a modified form of the invention.

In carrying out the present invention there is provided a casing 1 of any desired form, the same in the present instance being shown as of box-like construction and provided with a suitable carrying strap or bail 29, or with other means of support and transport. The casing 1 may be equipped with a lid 2 held in place by means of hinges 3.

Located within the casing 1 and preferably secured to one side wall thereof is a motor 4. The motor 4 may be operated in any desired manner. The shaft 5 of the motor 4 merges into or is operatively connected with the shaft 6 of a combined blower and suction device 7 which may be upheld upon one of the side walls of the casing 1.

The numeral 8 indicates any suitable mechanism whereby the direction of rotation of the motor shaft 5, and consequently the direction of rotation of the blower shaft 6, may be reversed.

Projecting from the blower and suction device 7 and prolonged through one end wall of the casing 1 is a primary pipe 9 equipped with a valve 10. Attached to the exposed end of the primary pipe 9 is a flexible tube 15 of any desired length, the same being equipped with a flaring section head 16. Branched off from the pipe 9 and ordinarily located outside of the casing 1 is a pipe 11 provided with a valve 12, there being a foraminous receptacle 14 connected with the end of the branch pipe 11.

Projecting from the combined blower and suction device 7 is a secondary pipe 17 which passes outside of the casing 1. Assembled with the exposed end of the secondary pipe 17 is a flexible tube 18 of any desired length, the same being connected as shown at 33 with a tube or neck 32 which, in its turn, merges into the body portion 30 of a suction head 19. The neck or tube 32 is stiff, and can be held and pointed in any direction with facility, the tube 18 being yieldable so that the head 19 may be inverted if desired. Viewed in bottom plan, the head 19 is of flat-iron shape and is tapered at one end as shown at 31. A removable frame 34 is connected by means of removable uprights 35 with the part 30 of the suction head. Removable screens 36 of large mesh extend across the suction head, the screens being removable so that the device may be adapted to handle cockroaches, locusts and other large insects.

Located within the casing 1 and ordinarily secured to one wall thereof is a container 20 having a reduced mouth 21, communicating with the pipe 17, the mouth 21 being deflected in the direction of the draft 100 of air through the pipe 17, so as to tend to create a vacuum or a partial vacuum in the container 20, thereby drawing outwardly, the contents of the container indicated at 27, it being obvious that if the part 22 stood at 105 right angles to the pipe 17, the air passing through the pipe 17 might tend to flow upwardly, displacing the contents 27 of the container 20. The outlet or mouth 21 is controlled by a valve 22 of any desired sort, 110 in the present instance shown as provided with a tapered top. It has been presup-

posed that the material in the container 20 is a dry powder, but if a liquid poison is used, the shape of the valve 22 of course will be changed. The valve 22 may be operated 5 through the medium of a rod 23 mounted to reciprocate in a spider 24 located within the container 20. The lid 21 may be provided with a slot 25 adapted to receive the rod 23 and the lid may be equipped with an opening 26 adapted to receive the push-button 8 or like device whereby the direction of rotation of the shaft 5 is reversed.

In practical operation, the container 20 is filled with any suitable substance indicated 15 at 27, which, when blown through the pipe 18, will kill or stupefy flies or other insects. At this point it may be stated that when the *Cimex lectularius* and like insects are to be dealt with, a tapered nozzle 28, shown in 20 Fig. 3, replaces the suction head 19, the nozzle 28 being adapted to direct the material into narrow cracks and other restricted places.

The valve 10 is open in operation and the 25 motor is put into operation to drive the blower 7. The valve 22 is raised slightly so that the poisonous material 27 in the container 20 may flow slowly into the pipe 17. Then, air charged with the poisonous material 27 is blown out through the pipe 18 and through the discharge head 19, insects in this manner being killed or stupefied. Then the valve 10 is closed and the valve 12 is opened, the direction of rotation of the 30 shaft 5 being reversed through the medium of the mechanism indicated at 8. Then a suction will be created through the pipe 18, insects previously killed or stupefied being drawn through the pipe 18 and being forced 35 outwardly through the pipe 9—11 into the foraminous receptacle 14 in which they will accumulate. During the operation which consists in sucking up the killed or stupefied insects, the valve 22 is in a closed position.

40 The screens 36 may be smeared with molasses or any other substance which will attract insects, the insects entering the head 19 when the same is inverted and is disposed bottom uppermost, as shown in Fig. 4. Then, when the blower is started, the insects will be sucked through the machine in the manner hereinbefore specified. Owing 45 to the tapered form of the head, indicated at 31, the head may be slid along a table or the like and it is to be noted that the tapered form of the head serves to increase the draft through the head. Further, owing to the shape of the head, the point 31 may be inserted into angles and corners where flies 50 or other insects might take refuge. The

head 19, being broader than the diameter of the pipe or neck 32 obviously increases the effective working area of the device.

If desired, the head may be reversed from the position shown in Fig. 1, so that its 65 mouth is upwardly disposed. Then, when a suction is created in the pipe 18 and attendant parts, flies or other insects which have been poisoned or rendered inactive may be collected in the head, the same acting 70 as a collecting dish or receptacle.

The structure may be mounted on a tripod T, if desired.

Having thus described the invention, what is claimed is:

1. In a device of the class described, a motor; a combined blower and suction device operatively connected with the motor; primary and secondary pipes projecting from the blower; a foraminous receptacle 80 into which the primary pipe discharges; a poison receptacle discharging into the secondary pipe; and means for reversing the motor.

2. In a device of the class described, a 85 motor; a combined blower and suction device operatively connected with the motor; means for reversing the motor; a primary pipe projecting from the blower; a valve in the primary pipe; a branch communicating 90 with the primary pipe; a valve in the branch; a foraminous receptacle into which the branch discharges; a secondary pipe projecting from the blower; and a poison receptacle 95 discharging into the secondary pipe.

3. In a device of the class described, a combined blower and suction device; a combined intake and outlet member in communication with the blower and suction device; a foraminous receptacle in communication with the blower and suction device; means for discharging poison into the intake and outlet member at the will of an operator; and means for reversing the 100 blower and suction device.

4. In a device of the class described, a combined blower and suction device; means for reversing the blower and suction device; opposed pipes projecting from the blower 110 and suction device; and means for discharging poison into one of said pipes at the will of an operator.

In testimony that I claim the foregoing as my own, I have hereto affixed my signature in the presence of two witnesses.

JOHN FRANCIS LE BARON.
